REGULATING SYSTEM

Lester G. Tubbs, Wilkinsburg, Pa., assignor to
Westinghouse Electric & Manufacturing Company, East Pittsburgh, Pa., a corporation of Pennsylvania

Application June 13, 1942, Serial No. 446,855

5 Claims. (Cl. 171—119)

This invention relates to regulator control circuits and in particular to improvements in time delay control circuits for electrical regulators.

In voltage regulators, the control apparatus is usually arranged to start movement of the regulator in a very short time after the voltage which is to be controlled has exceeded a predetermined variation from normal voltage. In most cases this method of operation is desirable in order to have the voltage brought back to normal as quickly as possible. There are certain cases, however, in which the voltage which is to be controlled varies quite rapidly, stay at an abnormal value for only a short time, and then return to normal or even go beyond the permissible value of voltage in the other direction. In such cases, by the time the movement of the regulator has taken place, the voltage may have changed to some other value, causing the operation of the regulator just completed to be of no value or even detrimental.

Heretofore attempts have been made to provide a time delay responsive action in the operation of the regulator, but the apparatus employed usually included parts which operated mechanically and were subject to wear, thereby requiring maintenance, or the apparatus necessitated an operation of the time delay device to interrupt the operation of the regulator.

It is an object of this invention to provide a new and improved regulator control system.

Another object of this invention is to provide a regulating system having time delay characteristics but which operates independently of such time delay for interrupting the operation of the regulator.

A more specific object of this invention is to provide a regulating system having a thermal time delay which is unaffected by changes in ambient temperature and to so control the regulator as to interrupt its operation independently of the operation of such time delay.

Other objects of this invention will become apparent from the following description when taken in conjunction with the accompanying drawing in which:

Figure 1 is a diagrammatic illustration of the apparatus and system provided in accordance with this invention.

Fig. 2 is a view in elevation with a part broken away of a preferred time delay apparatus employed in the circuit of Fig. 1;

Fig. 3 is an elevation view, partly in section, taken along the line III—III of Fig. 2;

Fig. 4 is an enlarged fragmentary view of a 55 neutral position illustrated when a predetermined

part of the apparatus of Figs. 2 and 3 taken along the line IV—IV of Fig. 3, and

Fig. 5 is an enlarged fragmentary view of another part of the apparatus of Figs. 2 and 3 taken along the line V—V of Fig. 3.

Referring to the drawing and in particular to Fig. 1 thereof, there is illustrated a regulating system for maintaining the voltage of the generator 10 substantially constant. The generator 10 is provided with an armature winding 12 and a field winding 14. As illustrated, the armature winding 12 is connected across a line comprising conductors 16 and 18 and the field winding 14 is connected to any suitable source of direct current. In this instance the source of direct current employed is an exciter generator 20 which may be driven in any suitable manner by a motor or other prime mover (not shown). The exciter 20 is connected by conductors 22 and 24 to the field winding 14, a motor operated field rheostat 26 also being connected in the exciter circuit with the field winding.

As illustrated, a pilot motor 28 is provided for operating the rheostat 26 and is connected thereto by means of the worm and gear drive 30. The rheostat 26 is of any well known construction and is provided with an adjustable contact arm 32 which electrically engages the resistor element. The rheostat motor 28 is provided with an armature winding 34 and field windings 36 and 38. An auxiliary control device comprising the relays 40 and 42 are disposed to be connected in circuit relation with the field windings 36 and 38, respectively, to control the operation of the motor 28 from a battery 44, as will be explained more fully hereinafter.

Since it is desired to control the operation of the relays 40 and 42 in accordance with changes in the voltage across the line conductors 16 and 18, a primary control device 46 is provided having its operating winding 48 connected by conductors 50 and 52 to the line conductors 16 and 18, respectively, whereby it is energized in accordance with the voltage on the generator 10.

The energization of the operating winding 48 of the primary control device 46 changes with the voltage on the generator 10 and operates a contact carrying arm 54 about its pivot 56 against the bias of a spring member 58 to actuate one or the other of contact members 60 and 62 into engagement with fixed contact members 64 and 66, respectively, depending upon whether the change in the voltage is an increase or decrease. Normally, the contact carrying arm 54 is in the neutral position illustrated when a predetermined

normal voltage is on the generator. The contact carrying arm 54 is of conductive material and is connected to conductor 50 by conductor 68.

As illustrated, a thermal time delay device 70 is disposed to be connected in circuit between the primary control device 46 and the control relays 40 and 42 of the rheostat motor 28. The thermal time delay device 70, shown diagrammatically in Fig. 1, is preferably of the type illustrated in Figs. 2 and 3. As illustrated, the device 70 comprises a pair of stationary contact members 72 and 74 disposed spaced apart but facing each other, and a pair of movable contact members 76 and 78 disposed for cooperating therewith for closing a predetermined circuit.

Each of the stationary contact members 72 and 74 is mounted on a resilient leaf member 80 which is secured to a support 82 mounted on the panel 84 by means of the conducting screw 86 and the connecting nut 88. As illustrated, the support 82 also carries an insulating member 90 on the side opposite the leaf member 80 for effectively insulating an adjusting member 92 therefrom. The adjuster 92 is an elongated screw member positioned through a suitable opening (not shown) in the housing of the time delay device, and is disposed to be turned to bear against the end of the insulated support member 82 to position the fixed contact member 72 or 74, as the case may be, relative to its cooperating movable contact member.

Each of the movable contact members 76 on 78 is carried on an elongated substantially U-shaped bimetallic element 84, one leg 96 of which is longer than the other leg 98, as more clearly shown in Fig. 3. The bimetallic elements 94 are so mounted that they tend to bend away from one another when heated. Each of the bimetallic elements 94 is mounted on an L-shaped supporting member 100, the ends of the legs of the thermal element being secured thereto by any suitable means.

As illustrated in Fig. 5, the longer leg 96 of the element 94 is secured to the support 100 by means of the rivet 102 which extends through an enlarged opening 104 in the leg, layers of insulation 106 and 108 being provided for effectively insulating the leg from the support member 100 and the rivet 102. The lower end of the leg 96 terminates in a curved end which forms a terminal clip 97 for a lead.

The mounting for the shorter leg 98 of the element 94 is illustrated in Fig. 4. As illustrated, the leg 98 is in electrical contact with one leg of the L-shaped support 100, the rivets 110 being very close fitting and providing an electrical path therebetween. The base of the support 100 is secured to the panel 84 by means of the screw member 112 and the connecting nut 114, terminal clips 116 and 118 being provided for making electrical connections thereto.

As illustrated in Fig. 2, the movable contact members 76 and 78 are held in spaced relation to each other by means of an insulating spacer member 120 which fits over projecting lugs 122 provided on the upper end of each of the elements 94. This spacer member 120 ensures correct operation of the movable contact members and prevents movement of either of the movable contact members in response to a change in ambient temperature.

Again referring to Fig. 3, the thermal delay device 70 is provided with a transformer 124 associated with the movable contact member 76

and a transformer 126 associated with the movable contact member 78. These transformers may be so assembled as illustrated as to operate on the same core member 128, the transformers being built in and carried by the housing of the thermal delay device.

Each of the transformers 124 and 126 is provided with a primary winding 130 and a secondary winding 132. The secondary winding is connected by leads 134 and 136 to the terminal clip 118 mounted on the support member 100 and the terminal 97 on the lower end of the longer leg 96, respectively, whereby the bimetal element 94 is connected in circuit with the secondary winding 132.

15 Likewise, the primary winding 130 of the transformer 124 is connected by leads 138 and 140 to a terminal clip 142 secured on the panel 84 by the screw 139 and connecting nut 141 and the terminal clip 116 carried by the support member 100, respectively, the terminal clip 116 being in electrical contact with the shorter leg 98 of the element 94. For convenience, the leads of only one of the transformers, namely 124, are illustrated in Figs. 2 and 3, although it will be obvious that similar leads and connections will be provided for the transformer 126 which is associated with the fixed contact member 74 and movable contact member 78.

Referring to Fig. 1, transformer 126 of the thermal delay device 70 is illustrated with its primary winding 130 connected to the fixed contact member 64 of the primary control device 46 by conductor 144 and to the conductor 52 by conductor 146. Likewise, one side of the secondary winding 132 of transformer 126 and one leg of the bimetal element is connected by lead 140 and conductor 144 to the fixed contact member 64, the other side of the secondary 132 being connected to the other leg of the thermal element 40 carrying the contact member 78.

In a similar manner, the primary winding 130 of transformer 124 is connected by conductor 148 to the fixed contact member 66 of primary control device 46 and to the conductor 52 by conductor 150. Likewise, one side of the secondary winding 132 of the transformer 124 and one leg of the bimetal element 94 is connected by lead 140 and conductor 148 to the fixed contact member 66, the other end of the secondary winding 132 being connected directly to the other leg of the bimetal member 94 which carries the movable contact member 76.

The fixed contact member 74 of the thermal delay device 70 is illustrated as being connected by conductor 152 to the operating winding of the relay 40, and thence by conductor 154 to the conductor 52. Similarly, the fixed contact member 72 is connected by conductor 156 to the operating winding of relay 42 and thence through conductor 154 to the conductor 52.

In operation, assume that the voltage on the generator 12 is at a normal voltage and the apparatus illustrated diagrammatically is substantially as shown. If, for any reason the voltage on the generator 12 increases, then the energization of the operating winding 48 of the primary control device 46 is increased to effect a movement of the contact carrying arm 54 in a clockwise direction about its pivot 56 against the bias of the spring 58 to actuate the movable contact member 60 into a circuit closing position with the fixed contact member 64. Such movement of the movable "lower" contact member 60 establishes a circuit which extends from line conductor 16

through conductor 50, conductor 68, the contact carrying arm 54, engaged contact members 60 and 64, conductor 144, the primary winding 130 of transformer 126, and conductors 146 and 52 to the line conductor 18. The energization of the primary winding 130 of transformer 126 induces a flow of current through the secondary winding 132 and the bimetal element 94 which carries contact member 78.

If the increase in the voltage on the generator 12 is a momentary increase then the energization of the operating winding 48 is of only a momentary value with the result that the movable contact member 60 is only momentarily in engagement with the fixed contact 64 and the transformer 126 is energized for so short a period of time that the bimetal element 94 which carries the contact member 78 is insufficiently heated to actuate the contact member 78 into engagement with the fixed contact member 74.

However, if the increase in the voltage on generator 12 is of sufficient duration, then the bimetal element 94 which carries the contact member 78 is so heated as to actuate the "lower" contact member 78 into engagement with the fixed contact member 74. It is to be noted that because of the insulating connector member 120 which connects the bimetal elements carrying the movable contact members, that the bimetal member 94 associated with the contact member 76 is moved at the same rate and in the same direction as the heated bimetal member 94 which carries the contact member 78.

When the contact member 78 is in engagement with the fixed contact member 74, a circuit is closed which extends from the lead conductor 16 through conductors 50 and 68, contact carrying arm 54, contact members 60 and 64, conductors 144 and 140, bimetal member 94, contact members 78 and 74, conductor 152, the operating winding of "lower" relay 40, and conductors 154 and 52 to the line conductor 18 to energize the operating winding of relay 40. When this circuit is established, the relay 40 is actuated to close the circuit to energize the winding 36 of motor 28 and effect the operation of the motor 28 to drive the contact arm 32 in a counterclockwise direction. This operation of the contact arm 32 connects more of the rheostat 26 in the field circuit of the generator 10 to decrease the energization of the field winding 14 and thereby decrease the voltage on the generator.

If at any time during the operation of the rheostat motor 28 the increase in the voltage on the generator 10 is removed from the line conductors 16 and 18, then the operation of the motor 28 is substantially instantaneously interrupted by the operation of the primary control device 46 to separate the contact members 60 and 64, thereby effecting the deenergization of the operating winding of the relay 40. Thus, although the initiation of the operation of the rheostat motor 28 is dependent upon the operation of both the primary control device 46 and the thermal time delay device 70, the operation is instantly interrupted by the operation of the primary control device 46 only, even though the thermal time delay device 70 is in a circuit closing position.

If, on the other hand, the change in the voltage in the generator 10 is a decrease, then the energization of the operating winding 48 of primary control device 46 is so decreased that the contact carrying arm 54 is actuated by the spring 58 in a counterclockwise direction to a position where the "raise" contact member 62 engages the

fixed contact member 66 to close a circuit through the primary winding 130 of the transformer 124. This circuit extends from the line conductor 16, through conductors 50 and 68, contact carrying arm 54, contact members 62 and 66, conductor 148, a primary winding of transformer 124, and conductors 150 and 52 to the line conductor 18.

The energization of the primary winding 130 of transformer 124 effects a flow of current through the secondary winding 132 and the bimetal element 94 which carries the movable contact member 76 to heat the bimetal member and cause it to bend to a position where the "raise" contact member 76 engages the contact member 72. When the bimetal member 94 which carries the contact member 76 is thus actuated, a circuit is closed which extends from the line conductor 16, through conductors 50 and 68, contact carrying arm 54, contact members 62 and 66, conductors 148 and 140, the bimetallic element 94, contact members 76 and 72, conductor 156, the operating winding of "raise" relay 42 and conductors 154 and 52 to the line conductor 18 to effectively energize the relay 42.

When the relay 42 is energized, it establishes a circuit to effect the energization of the field winding 38 of the rheostat motor 28 whereby the motor 28 is operated to actuate the contact arm 32 in a clockwise direction to cut out a portion of the rheostat 26 from the field circuit of the generator 10. Removal of a portion of the rheostat 26 increases the energization of the field winding 14 and thereby increases the voltage on the generator 10.

Whether the change in the voltage on the generator be an increase or a decrease, the thermal time delay device 70 operates in a similar manner but in a reverse direction, depending upon the direction of the change. Likewise, regardless of the direction of the change, the operation of the rheostat motor 28 is dependent upon the operation of both the primary device and the thermal time delay device but the primary control device operates independently of the time delay device to interrupt the operation of the motor.

The apparatus and system of this invention provides a simplified regulation of voltage requiring a minimum of mechanical parts which may demand maintenance. Further, because of the time delay provided, operation of the regulator is decreased to a minimum, small rapid changes in the voltage of the generator having no effect on the regulator. In addition, provision is made for instantaneously interrupting the operation of the regulator when required by the voltage of the generator to prevent overregulation of the voltage.

Although this invention has been described with reference to a particular embodiment thereof, it is, of course, not to be limited thereto except in so far as is necessitated by the scope of the appended claims.

I claim as my invention:

1. In a regulating system, in combination, an electric circuit the voltage of which is to be regulated, an automatic voltage regulator for said circuit, a control circuit for the regulator, the control circuit including a primary control device connected to respond to the voltage of said circuit, means under the control of the primary control device for controlling the operation of the regulator, and a thermal responsive time delay device connected in circuit with the controlling

means for delaying the response thereof to the primary control device, the time delay device and the primary control device being disposed to be connected in series circuit relation with each other and the controlling means whereby the controlling means is dependent upon the operation of both the primary control device and the time delay device to effect the operation of the regulator but dependent upon the operation of the primary control device only to interrupt the operation of the regulator.

2. In a regulating system, in combination, a dynamoelectric machine having a field winding the voltage of which is to be regulated, a rheostat for controlling the energization of the field winding, a reversible motor for operating the rheostat, a primary control device connected to respond to the voltage of the dynamoelectric machine, means under the control of the primary control device for controlling the operation of the rheostat motor, and a thermal responsive time delay device connected in circuit with the controlling means for delaying the response thereof to the primary control device, the time delay device and primary control device being disposed to be connected in series circuit relation with each other and the controlling means whereby the controlling means is dependent upon the operation of both the primary control device and the time delay device to effect the operation of the motor but dependent upon the operation of the primary control device only to interrupt the operation of the motor.

3. In a regulating system, in combination, an electric circuit the voltage of which is to be regulated, an automatic voltage regulator for said circuit, a control circuit for the regulator, the control circuit including a primary control device connected to respond to the voltage of said circuit and having separate "raise" and "lower" contact members, means comprising a pair of auxiliary control devices having contact members for controlling the operation of the regulator and having windings disposed to be selectively connected to the "raise" or "lower" contact members of the primary control device, and a time delay device disposed to delay the response of the auxiliary control devices to the primary control device, the time delay device having a pair of contact members disposed to selectively connect the windings of the auxiliary control device in series circuit relation with an associated contact member of the primary control device, a thermoresponsive element associated with each of the time delay contact members and disposed to actuate it, and means associated with each of the thermoresponsive elements dependent upon the operation of the primary control device for selectively heating the thermoresponsive elements to actuate the control member associated therewith and selectively energize a winding of the auxiliary control devices to control the operation of the regulator, the energization of the winding being dependent upon the establishment of the series circuit connection between the primary control device and the auxiliary control device by the time delay device, the primary control device operating under predetermined conditions to interrupt the series circuit independently of the operation of the time delay device to deenergize the winding and interrupt the operation of the regulator.

4. In a regulating system, in combination, an

electric circuit the voltage of which is to be regulated, an automatic voltage regulator for said circuit, a control circuit for the regulator, the control circuit including a primary control device connected to respond to the voltage of said circuit and having separate "raise" and "lower" contact members, means comprising a pair of auxiliary control devices having contact members for controlling the operation of the regulator and having windings disposed to be selectively connected to the "raise" or "lower" contact members of the primary control device, and a time delay device disposed to delay the response of the auxiliary control devices to the primary control device, the time delay device comprising a contact member associated with each of the windings and the primary control contact member associated therewith, a thermoresponsive element disposed to actuate each of the time delay contact members, and means associated with the thermoresponsive element and responsive to the operation of the primary control device for heating the element to effect the actuation of the contact member associated therewith to connect the winding and the primary control contact member in series circuit relation to energize the winding, the primary control device being operative independently of the time delay device when the time delay contact member is in its circuit establishing position to effect the substantially instantaneous deenergization of the winding to interrupt the operation of the regulator.

5. In a regulating system, in combination, an electric circuit the voltage of which is to be regulated, an automatic voltage regulator for said circuit, a control circuit for the regulator, the control circuit including a primary control device connected to respond to the voltage of said circuit, separate "raise" and "lower" contact members for the primary control device disposed to be actuated to a circuit closing position under predetermined operating conditions of the primary control device, a "raise" and a "lower" auxiliary control member having a contact member corresponding to the "raise" and "lower" contact members of the primary control device, a winding for each of the auxiliary control members disposed to be selectively connected to the "raise" and "lower" contact members of the primary control device to control the operation of the regulator, and a time delay device disposed to delay the connection of the windings to the primary control contact members to delay the operation of the regulator, the time delay device comprising a "raise" and a "lower" contact member, a thermoresponsive member associated with and disposed to actuate each of the time delay contact members, a transformer electrically connected to each of the thermoresponsive elements disposed to be selectively energized when the primary control device is actuated to a circuit closing position to heat the element connected thereto and actuate its contact member to selectively connect a winding of the auxiliary control device to one of the primary control contact members and thereby effect the energization of the winding, the primary control device being operative independently of the time delay device when the time delay contact member is in its circuit closing position to effect the substantially instantaneous deenergization of the winding to interrupt the operation of the regulator.

LESTER G. TUBBS.
